Revlon, Inc., New York, N. Y., a corporation of Delaware

Application August 29, 1956, Serial No. 42,775

Term of patent 14 years

(Cl. D86—10)

Fig. 1 is a view in elevation of a lipstick container showing my new design; and

Fig. 2 is a top end view.

The medial band shown in Fig. 1 is continued at the side opposite that in Fig. 1 and of the same width as shown at the side margins of Fig. 1. The said medial band has scalloped edges intermediate which are synthetic faceted jewels. The design opposite that shown in Fig. 1 as to the main body, is the same as in Fig. 1.

I claim:

The ornamental design for a lipstick container, as shown and described.
